(57) CLAIM

The ornamental design for an element of an adjustable luminaire, as shown and described.

DESCRIPTION

FIG. 1 is a top perspective view of an element of an adjustable luminaire showing my new design.

FIG. 2 is a top view thereof;

FIG. 3 is a bottom view thereof;

FIG. 4 is a front view thereof;

FIG. 5 is a rear view thereof;

FIG. 6 is a right-side view thereof; and,

FIG. 7 is a left-side view thereof.

The portions of the element of an adjustable luminaire shown in broken lines form no part of the design.
